John M. Thompson,

Inventor

By G. Kennedy
Attorney

UNITED STATES PATENT OFFICE

JOHN M. THOMPSON, OF THORPE, IOWA

GATE-SUPPORTING MEANS

Application filed October 27, 1928. Serial No. 315,442.

My invention relates to improvements in supporting means for gates and the like, and the object of my improvements is to perfect a supporting structure of this class which 5 may be easily and quickly employed for supporting a gate at different vertical heights to freely swing to and fro in any adjusted position of the gates relative to the support.

Another object is to effect improvements 10 in the invention of gate supporting means, which were patented to me by United States Patent No. 1,616,558, issued February 8, 1927.

I have accomplished the above objects by 15 the means which are hereinafter described and claimed, and which are illustrated in the accompanying drawings, in which Fig. 1 is a front elevation of my improved gate supporting means, shown as supporting a 20 swinging gate at a desired height of adjustment from the ground. Fig. 2 is a view partly in section and partly in elevation, with parts broken away, of the gate supporting means. Fig. 3 is a top plan of the structures of said Fig. 2, with a part in cross section.

It will be understood that minor modifications of my improvements are covered within the principles of this invention and of the 30 appended claims.

1 is a rear tubular post which may be fixedly mounted on any suitable base or the ground itself, the post being closed at the bottom and open at the top and containing 35 in its interior bore a vertically disposed coiled compression spring 4. The numeral 12 denotes a pair of like mating hollow members, which may be castings or stampings, whose lower part when assembled contains 40 an interior hollow 17 opening downwardly and of an interior diameter suitable to permit them to fit loosely and rotatably upon the top portion of the post 1, the inner wall of this hollow 17 having an annular groove 15 45 to receive and movably interlock with an annular flange 16 on the post 1, so that the members 12 at their parts 14 may freely swing horizontally upon the post and be retained thereon. The upper parts of the members 12—14 have a bore 18 of less diameter

than the bore or hollow 17 to loosely seat the lower portion of a cylindrical standard 5 whose upper part is reversely bent downwardly in parallel to provide a goose-neck 6.

The lower end of the standard 5 is supported upon the upper end of the spring 4 within the upper part of the post 1. The numeral 10 denotes the hollow tubular metal frame of a horizontally elongated and wire netted gate of a well-known type whose front 55 stile is adjacent a front post 2, the latter having a spring clip 3 mounted thereon in a position and at a height permitting it to clip removably the front stile of the gate in any 60 vertically adjusted position of the latter. 65 The free extremity of the gate is supported by a brace-rod 11 connected to the upper bend of the standard 5.

The rear stile of the gate 10 is secured fixedly to the goose-neck or bend 6 by pairs of 70 clamps 7 and 8 at top and bottom, and a clamping pair of members 9 are used to support the rear lower part of the gate, being fixedly clamped to the rear stile of the gate 75 below the lower clamps 8, and being loosely or rockingly mounted upon the post 1.

I have adopted the following described means for releasably securing the standard 5 in a vertical position of adjustment relative to the post 1 and its head members 12—14. 80 As best shown in Fig. 3, the mated members aforesaid at 12 where opposite faces are flattened, are apertured horizontally and in parallel on opposite sides of the standard 5 to loosely receive the pair of headed bolts 19, 85 and to also traverse apertures in the outwardly projecting extremities of a pintle 25 upon which between said bolts an eccentric 24 is rockingly mounted. This eccentric or eccentric cam bears against one flat face of the 90 abutting member 12, and has a projecting handle 26. On the opposite ends of the bolts 19 are mounted upon their threads nuts 20 engaging the opposite flat face of the member 12, a split compression spring 21 is next 95 mounted on each bolt next to a washer 22 and a terminal nut 23 permitting adjustments of the tension of the spring.

It will be seen that when the tension of the spring 21 is properly adjusted, the handle 26 100

may be swung downwardly after the other spring 4 has been allowed to react to propel the standard 5 together with said gate to a desired height from the ground, the eccentric cam then acting upon the members 12 through the bolts 19, to tightly clamp the members 12 upon the standard 5, thus retaining the gate in the selected position, where it may be freely swung to and fro.

10 It will be observed that the clamping means described are simpler than those of said Patent No. 1,616,558, effecting an economy in manufacture, positioned more conveniently, and are free from the bend 6 of the standard 5, suiting the latter and said bend for particular uses and locations.

Having described my invention, what I claim as new, and desire to secure by Letters Patent, is:

20 1. In combination, a fixed support, a tensionally controlled member movable vertically relatively to and also rockingly mounted upon said support, a gate secured upon said member to swing therewith to and fro horizontally, and means for releasably holding said member and gate in a vertically adjusted position upon said support while permitting the member and gate to swing freely, consisting of separably mating clamps 25 mounted loosely upon said member and upon the upper part of the support only, said clamps being apertured in alignment on opposite sides of the said member, stems seated loosely in said apertures connected at one end 30 by a pintle, an eccentric cam rockingly mounted on said pintle and having its cam edge bearing against said clamps, and tensionally controlled securing means adjustably mounted upon the opposite ends of said stems 35 against said clamps, whereby the cam may be rocked to clamp the clamps tightly upon said member while allowing the lower parts of the clamps to seat loosely rockingly upon said support.

40 2. In combination, a tubular support open at the top and closed at the bottom, a coiled compression spring seated in the hollow of said support, a reversely bent member having one depending leg seated in the hollow of 45 said support upon said spring, a gate secured upon the other leg of said member rigidly to swing therewith relatively to said support, a pair of like hollowed clamping elements mating and having aligned bores of 50 different diameters of which the upper bore loosely fits upon said member and the lower bore loosely fits upon the upper part of said support, the wall of the lower bore having an annular recess, the outer wall of the support having an annular flange fitting loosely within said recess, and adjustable tensional means for compressing said clamping elements together to cause them to clamp tightly upon said member to allow said elements to rock together with the gate horizon-

tally upon said support, the clamping elements remaining loosely rockable upon said support in any position of the clamping elements.

In testimony whereof I affix my signature. 70
JOHN M. THOMPSON.
